The ornamental design for a capsule containing washing products, as shown and described.

DESCRIPTION

FIG. 1 is a front, right side, and top side perspective view of an embodiment of a capsule containing washing products showing a circular insert and washing powder of the present design;

FIG. 2 is a top side plan view of the capsule containing washing products of FIG. 1;

FIG. 3 is a bottom side plan view of the capsule containing washing products of FIG. 1;

FIG. 4 is a right side elevational view of the capsule containing washing products of FIG. 1, the left side being substantially a mirror image of the right side;

FIG. 5 is a front side elevation view of the capsule containing washing products of FIG. 1, the back side being a mirror image of the right side;

FIG. 6 is a front, right side, and top side perspective view of an embodiment of a capsule containing washing products showing a circular insert of a first color and washing powder of a second color of the present design;

FIG. 7 is a top side plan view of the capsule containing washing products of FIG. 6;

FIG. 8 is a bottom side plan view of the capsule containing washing products of FIG. 6;

FIG. 9 is a right side elevational view of the capsule containing washing products of FIG. 6, the left side being a mirror image of the right side;

FIG. 10 is a front side elevational view of the capsule containing washing products of FIG. 6, the back side being a mirror image of the front side;

FIG. 11 is a front, right side, and top side perspective view of an embodiment of a capsule containing washing products showing a circular insert of a first color and washing powder of a second color of the present design;

FIG. 12 is a top side plan view of the capsule containing washing products of FIG. 11;

FIG. 13 is a bottom side plan view of the capsule containing washing products of FIG. 11;

FIG. 14 is a right side elevational view of the capsule containing washing products of FIG. 11, the left side being a mirror image of the right side;

FIG. 15 is a front side elevational view of the capsule containing washing products of FIG. 11, the back side being a mirror image of the front side;

FIG. 16 is a front, right side, and top side perspective view of an embodiment of a capsule containing washing products showing a yellow circular insert and blue washing powder of the present design utilizing horizontal solid-line and vertical solid-line hatching to denote the yellow color of the circular insert and horizontal solid-line hatching to denote the blue color of the washing powder;

FIG. 17 is a top side plan view of the capsule containing washing products of FIG. 16 utilizing horizontal solid-line and vertical solid-line hatching to denote the yellow color of the circular insert and horizontal solid-line hatching to denote the blue color of the washing powder;

FIG. 18 is a bottom side plan view of the capsule containing washing products of FIG. 16 utilizing horizontal solid-line hatching to denote the blue color of the washing powder;

FIG. 19 is a right side elevational view of the capsule containing washing products of FIG. 16, the left side being a mirror image of the right side utilizing horizontal solid-line and vertical solid-line hatching to denote the yellow color of the circular insert and horizontal solid-line hatching to denote the blue color of the washing powder; and,

FIG. 20 is a front side elevational view of the capsule containing washing products of FIG. 16, the back side being a mirror image of the front side utilizing horizontal solid-line and vertical solid-line hatching to denote the yellow color of the circular insert and horizontal solid-line hatching to denote the blue color of the washing powder.

In the drawings, the broken lines show portions of the capsule containing washing products and form no part of the claimed design.
